UNITED STATES PATENT OFFICE.

ALFRED E. GRAVES, OF BOSTON, MASSACHUSETTS, ASSIGNOR TO PACKAGE CONFEC-TIONERY COMPANY, A CORPORATION OF MASSACHUSETTS.

ASSORTING-MACHINE.

1,101,124.

Specification of Letters Patent. Patented June 23, 1914.

Application filed March 19, 1913. Serial No. 755,388.

To all whom it may concern:

Be it known that I, ALFRED E. GRAVES, of Boston, in the county of Suffolk and State of Massachusetts, have invented certain new and useful Improvements in Assorting-Machines, of which the following is a specification, reference being had to the accompanying drawings, forming part thereof.

10 This invention has reference to improvements in machines for assorting sugar or candy wafers or other articles and for arranging the assorted articles in stacks which stacks are delivered to a suitable receiving apparatus for a further operation or for transference to another mechanism in which a further operation is or may be effected.

One object of this invention is to so construct a machine of this nature that stacks 20 of articles may be progressively formed by the intermittent feeding of individual articles from different sources of supply and the stack so formed may be delivered without disarrangement of its constituent elements.

Another object of this invention is to so construct a machine of this nature that the stacks of fragile or brittle articles may be 30 progressively formed without shock to the articles so that danger of breakage of the articles is practically eliminated.

Another object of the invention is to improve the construction and operation of the 35 stack forming receptacles.

Other objects of the invention will appear from the following description.

To attain the objects of this invention recited above and others hereinafter more 40 fully described the invention consists in such novel features of construction and combination of parts as are pointed out in the following description and recited in the claims.

45 Referring to the drawings, Figure 1, represents a plan elevation, with a portion indicated by dotted lines, of the upper portion of a machine embodying my invention.

Fig. 2, represents a fragmentary sectional view, partly in elevation, on the line 2—2 of Fig. 1. Fig. 3, represents an enlarged fragmentary front elevation of a portion of the machine. Fig. 4, represents a fragmentary sectional view on the line 4—4 of Fig. 2. Fig. 5, represents a fragmentary

side elevation, partly in section, of the portion of the machine represented in Fig. 3. Fig. 6, represents a fragmentary plan elevation of a portion of the machine represented in Fig. 5. Fig. 7, represents an enlarged fragmentary plan elevation of a portion of the machine. Fig. 8, represents a fragmentary front elevation, partly in section, of same. Fig. 9, represents an enlarged fragmentary detail sectional view 65 on the line 9—9 of Fig. 1. Fig. 10, represents a sectional view on the line 10—10 of Fig. 9. Fig. 11, represents an enlarged fragmentary sectional view, partly in elevation, on the line 11—11 of Fig. 1. Fig. 12, represents a sectional view, with parts removed, on the line 12—12 of Fig. 2. Fig. 13, is a plan view of one end of a portion of the machine. Fig. 14, is a side elevation of same. 75

Like reference characters designate corresponding parts throughout.

Secured to the tubular standard 10 which is provided with a base 11, is an annular bracket 12. Supported by the latter, near 80 its periphery, are a plurality of vertical wafer containers or stack supports 13, each consisting of the base 14, rods 15 and the mouth piece 16. Said wafer containers are further supported by being secured near 85 their upper ends, to the periphery of the annular bracket 17 fixed to the standard 10. The wafer *w* may be placed in each of said containers by passing them through its mouth piece 16 down between its rods 15, through 90 the circular aperture 18 in its base 14 and down onto its feeding mechanism 19. All of the latter are alike and each consists of the radially disposed supporting and guiding plate 20 secured to the top of the bracket 12 95 and extending through a slot in the base of one of said wafer containers, and the feeding plate 21 which is guided and supported by the plate 20. Pivoted at one end on the lug 22 fixed to the rear end of said feeding plate 100 is the link 23 and the other end of said link is pivoted on the lower end of the lever 24. The latter is pivoted at 25 on a bracket 26 fixed to the standard 10 and the upper end of said lever engages the annular groove 27 105 in the sleeve 28 which is guided by the standard 10. Extending through apertures in said sleeve, through slots 29, in said standard and through an aperture in the vertical reciprocating rod 30 is a cross bolt 31 secured 110

to said sleeve by nuts on its ends. The lower end of said rod is provided with the cam roll 32 which is held in engagement with the cam 33 on the shaft 34, hereinafter described, by gravity, and by the action of the helical spring 35. It will be understood that the rotation of said shaft reciprocates the feeding plate 21 through the cam 33, cam roll 32, rod 30, cross bolt 31, sleeve 28, lever 24, link 23 and lug 22 and that said reciprocation will be controlled by the contour of said cam. Said feeding plate is provided with the circular aperture 36 which, when said feeding plate is at the limit of its inward movement, is directly in line with the wafers *w* contained in the wafer container 13, and in said position, the wafers drop by gravity so that the bottom one *w'* will be contained in said aperture and be supported by the plate 20. The outward movement of said feeding plate slides this wafer *w'* on the plate 20 until said feeding plate has reached the limit of said movement when said wafer drops by gravity through the aperture 37 in the plate 20. Normally, directly below each of the apertures 37 is the stack forming wafer delivery tube or receptacle 38, pivoted at 39 on the hanger 40 which is secured to the annular revolving bracket 41, hereinafter described. Said stack forming wafer delivery tubes or receptacles are spaced an equal distance apart around said revolving bracket. The latter is adapted to be intermittently rotated on ball bearing 43 between the lower end of its hub 44 and the collar 45 secured to the standard 10, by the pawl 46 which engages one of the notches 47 spaced an equal distance apart on the under edge of the rim 48 on the bracket 41. (Figs. 7 and 8). Said pawl is pivoted on the outer end of the arm 50 and is normally held in engagement with one of said notches by the spring 51. The inner end of said arm is supported on the hub 44 of the bracket 41. (Fig. 2).

The arm 50 is oscillated by the link 52, one end of which is pivoted at 53 to said arm and the other end is pivoted to the lever 54. The latter is provided with a pivot pin 55 which engages a slot 55^a in a standard 56 secured to the bed 58 of the machine. The pivot end of said lever is pressed upwardly so that the pivot pin normally engages the top of the slot 56 by the action of the expansion spring 57 which engages the under side of said pivot end and the lug 57^a on said standard. The inner end of the horizontal arm of said lever is provided with the cam roll 60 which engages the groove in the cam 61 fixed to the shaft 34. The movement of the upper end of the vertical arm of the lever 54 is guided by the guide bar 61 fixed to the standard 62 projecting from the bed 58. Fixed to the shaft 34 is a cam 63 which is engaged by a cam roll on the inner end of a

lever 64. The latter is pivoted at 65 on the standard 66 which is on the bed 58 and to the outer end of said lever is pivoted the lower end of the link 67. The upper end of the latter is pivoted to the lower end of a lock bolt 68 which passes through and is guided by a casing 69 screwed to a plate 70 secured to the standard 62. The upper end of said lock bolt, by the action of the spring 71, which is attached at one end to the lever 64 and at the other end to the standard 62, normally engages one of the V shaped notches 72 spaced an equal distance apart, around the under side of the rim 48 on the bracket 41.

It will be understood that the lock bolt 68 is moved out of engagement with the notch 92 by the working contour of the cam 63 through its cam roll, lever 64 and link 67. Immediately after the lock bolt 68 is moved out of engagement with the notch 72 the bracket 41 is rotated in the direction of the arrow shown in Fig. 8 by the pawl 46 through the arm 50, link 52, lever 54, cam roll 60 and cam 61, until the next notch 72 has been moved into the path of said lock bolt, when the latter is allowed by the cam 63 to be moved into said notch by the action of the spring 71. Simultaneously with the completion of the last movement, the pawl 46 comes to rest and on the return movement disengages from the notch 47 against the action of the spring 51 and at the limit of the return movement it snaps into the next notch. The lateral movement of said pawl is controlled by the cam 61. It is to be understood that the movements of the bracket 41 are equal and that after each movement it is rigidly held stationary. The outer end of the arm 50 may be supported by the pawl 46 bearing on the supporting bar 74 which is formed on the plate 70.

Projecting from the bottom of the stack forming receptacle 38 is the hanger 76 and extending through the latter and through said bottom is the plunger 77 consisting of the head 78 made of felt or other resilient material and the elongated rod 79 provided with the reduced portion 80 near its end which forms shoulders 81. Supporting a majority of said plungers is the annular inclined track 77^a, on the highest end 77^b of which is pivoted the guiding lever 78^a at 78^b. (Figs. 1, 2, 13 and 14.) The inner end of said lever is normally sustained in the position shown in Fig. 13 by the spring 78^c. Secured to the hanger 76 is the bracket 82 provided with the stud 83 which is adapted to be received by the elbow slot 84 in the lever 85, the lower end of which is pivoted on a bracket 86 projecting from the bed 58 of the machine. Pivoted on said lever is one end of the link 87, the other end of which is pivoted on the lever 88 which is pivoted on the bracket 89 on the bed of the machine.

Said lever is provided with the cam roll 90 which engages the groove in the barrel cam 91 on the shaft 34. When the stud 83 has been moved into the path of the elbow slot 84 in the lever 85, in the manner hereinafter described, the latter is swung inwardly, causing said slot to engage the stud 83 thereby swinging said receptacle 38 on its pivot 39 from its normally vertical position to a horizontal position.

Fixed to the bracket 12 is the guiding plate 95 which is adapted to receive slots in the end of said receptacle 38 during the latter's oscillating movement and it is cut away at 96 to allow said receiving tube to be moved about the standard 10. Near the completion of the downward oscillation of said receptacle 38, the end 80 of the plunger rod 79 engages a recessed lug 97 on the carriage 98. The latter is supported and guided by a bar 99 supported by the standard 10 and on its under edge is the rack 100 which meshes with the gear segment 101. The latter is pivoted on the bracket 102 and is oscillated by the arm 103, link 104, lever 105 pivoted on the bracket 106, the cam roll 107 on said lever engaging the groove in the barrel cam 108 on the shaft 34 with the assistance of the spring 109 which is connected at one end to the lever 105 and at the other end to the bracket 102. After the end of the rod 79 engages the recess in the lug 97 the carriage 98 is moved forward by the segment 101 and said lug engages the shoulder 81, thereby causing said plunger to move forward with said carriage.

When a receptacle 38 is about to receive its first wafer its plunger is supported by the end 77^b of the track 77^a, so that the head of said plunger is slightly below the open end of said receptacle and as the wafers drop into said receptacle said plunger is allowed to gradually drop by the incline of said track and when said receptacle is filled its plunger slides from the lower end 77^c of said track. The distance that said plunger drops while sliding on said track from one feeding mechanism 19 to another is equal to the thickness of a wafer. As the head of a plunger supports the wafers after they have entered a receptacle the gradual drop of said plunger will equalize and minimize the distance that said wafers drop from a feeding mechanism 19 into said receptacle. When a plunger reaches the lever 78^a it swings said lever in the direction of the arrow shown in Fig. 13 which allows said receptacle to be swung into its horizontal position and its plunger forced forward, as hereinbefore described. During the latter movement of said receptacle its plunger disengages from said lever which allows the latter to be returned to its initial position by the spring 78^e. The carriage 98 is moved back by the same mechanism as accomplished its forward movement

and during the first part of said back movement it carries said plunger with it until the head of said plunger has passed the end of the guiding plate 95 when said plunger is disengaged from said carriage and is 70 swung downwardly by the lever 85. The inner arm of the lever 78^a is of sufficient length to be engaged by the end of said plunger during the latter movement of said delivery tube and is suitably curved to sustain said 75 plunger in the same relative position to said receptacle as it was when disengaged from said carriage. As said lever is in effect a continuation of the highest end of said track, said plunger will ride onto said track while 80 said receptacle is moving to receive its first wafer. The rib 77^d, on said track and the stops 38^c fixed to the bracket 41 sustain said receptacles and plungers in a substantially vertical position while the latter rides on 85 said track.

When the receptacle 38 is in a horizontal position its open end extends slightly into and is in line with the semi-cylindrical delivery tray 111. The latter consists of two 90 elongated leaves 112 and 113 with their outer edges secured to rods 114 and 115, respectively, which are pivoted in the end plates 116 and 117. The end plate 117 is recessed to allow a free passage from said 95 receptacle 38 into said tray and is secured to the cross bar 118 which is fixed to two standards 119 projecting from the bed of the machine. The leaves 112 and 113 are held normally, closed by leaf springs 120 100 fixed to the cross bar 118 and bearing against the ends of arms 121 on the rear ends of the rods 114 and 115. (Figs. 3, 5 and 6.)

Fixed at one end to the bracket 122 projecting from the end plate 117 is the stationary rod 123 and the other end of said rod is fixed to the bracket 124 projecting from the end plate 116. Mounted and adapted to slide on the rod 123 is a sleeve 125, provided with a bracket 126 which extends into the tray 111. On the inner end of said bracket is the pad 127 and the vertical plate 128 having the inclined edge 129. The pad 127 is moved toward the receiving end of the tray 111 by the weight 132 connected by the cord 133 to the stud 134 projecting from the sleeve 125. Said cord passes over a pulley 135 on the bracket 136 projecting from the cross bar 118. Secured to one of the bars 137, which connect the end plates 116 and 117, is the vertical frame 138 provided with lugs 139. Extending through and guided by said lugs are rods 140, the lower ends of which carry the discharge member 141 and the upper ends are secured 115 to the cross bar 142 and to the upper extremities of the wafer guiding plates 143 and 144. The discharge member 141 is reciprocated by the link 145 connecting the cross bar 142 to the arm 146 fixed to the 120 125 130 135 140 145 150 cross bar 142 to the arm 146 fixed to the 130

shaft 147 which is journaled in brackets 148 projecting from the frame 138. On the rear end of said shaft is secured the arm 149 connected by the link 150 to the lever 151. The latter is pivoted on the bracket 152 projecting from the bed plate 50, and is provided with the cam roll 153 which is held in engagement with the cam 154 on the shaft 34, by the spring 155. (Figs. 2, 3, 4 and 12.)

10 The shaft 34 is journaled in bearings 157 and may be driven by any suitable driving and clutching means, *e.g.*, in Fig. 2 is shown the continually rotating gear 158 loosely mounted on the rear end of said shaft and provided with sockets 159 which are adapted to receive the stud 160 projecting from the arm 161 pivoted on said shaft. The stud 160 is thrown into engagement with one of the sockets 159, thereby forcing said shaft to rotate with said gear, by the spring 162. The lever 163 is pivoted on the base 11 and its lower arm is connected by the rod 164 to the foot lever 165. The upper end of the lever 163 is provided with an inclined surface 166 which is normally held in the path of the end of the arm 161 by the spring 167. When the end of the arm 161 strikes the inclined surface 166 it is thrown out of engagement with the gear 158 and rides down on said inclined surface until it engages the stop 166^a which prevents further rotation of said shaft. It is to be understood that in order to operate the machine the end of the lever 163 must be thrown out of the path of the end of the arm 161 and this is accomplished through the link 164 and foot lever 165.

As all the feeding mechanisms 19 operate simultaneously, it is advisable to first load 40 with wafers in the manner hereinbefore described, the wafer container 13^a which deposits the first wafer in the receptacle 38 and then after the feeding devices have operated once, to load the next wafer container 13^b 45 and so on, so that when each receptacle 38 reaches the delivery tray 111 a wafer has been deposited therein by each delivery mechanism from its wafer container or stack holder. (Fig. 1). It is to be understood 50 that the number of wafers deposited in each receptacle will depend upon the number of wafer containers that are loaded. The drawings show four more receptacles than wafer containers but it is obvious that only one 55 more receptacle than wafer container is necessary. When a delivery tube has received a wafer from each of said wafer containers and has reached the delivery tray 111 it is 60 swung down into its horizontal position and the forward movement of the plunger 77 slides the stack of wafers from said delivery tube into said delivery tray against the pad 127 which sustains each wafer in an upright position. At the completion of the forward stroke of said plunger its head extends

slightly beyond the vertical plane of the guiding plate 144 and the inclined surface 29 of the plate 28 is in a position to be engaged by the guiding plate 143. Then said guiding plates and the discharge member 70 75 141 move downwardly, the guiding plate 143 engaging the inclined surface 29 which moves the pad 127 sufficiently away from said wafers to allow said guiding plate to pass between said pad and said wafers and 75 80 the guiding plate 144 forces the head 78 sufficiently away from said wafers to allow said guiding plate to pass between said wafers and said head. The plunger 77 is then moved back and the delivery tube is 80 85 swung up into its vertical position. During the latter movement the discharge member engages the column of wafers and forces them to open and to pass down between the leaves 112 and 113 of the delivery tray 111 85 90 against the action of the springs 120. (Fig. 4). The guiding plates 143 and 144, as they move with the delivery member 141, prevent lateral movement of said wafers. On the table 170 secured to the standard 119 may be 90 95 supported a suitable receptacle for receiving the wafers. In order that the discharge member 141 will not injure the wafers the dwell 171 on the contour of the cam 154 retards the downward movement of said discharge member when about to engage said wafers. After the latter operation, the discharge mechanisms return to their initial 100 positions ready to receive and discharge the column of wafers from the next receiving tube.

If the bracket 41 is forced to rotate after a wafer has become accidentally dislodged or a part of the machine has got out of order, serious damage may result and for this reason it is desirable not to rotate said bracket after it is thus hindered. In view of this, the pivot pin 55, on the lever 54, the slot 55^a in the standard 56 and the spring 57, hereinbefore described are provided, so that when more than the usual amount of power is required to rotate the bracket 41, the link 52 will not be moved longitudinally, as is required to rotate the bracket 41, but will be swung downwardly on its pivot 175, 110 115 as the pivot end of the lever 54 will move downwardly by overcoming the expansion of the spring 57. (Fig. 8.)

While I have herein disclosed a single embodiment of my invention, it is to be understood, that it is but one of many which might be employed and still be within the scope of the following claims.

Having thus described my invention I claim as new and desire to secure by Letters 125 Patent—

1. An assorting machine comprising a circular series of stack holders, a stack forming receptacle, a rotary carrier for said receptacle, means for operating said carrier, and 130

- means for transferring articles in succession from said stack holders to said receptacle.
2. An assorting machine comprising a circular series of stack holders, a stack forming receptacle, a rotary carrier for said receptacle, and intermittently operating means related to each of said stack holders for transferring articles in succession from each of said holders to said receptacle.
- 10 3. An assorting machine comprising a circular series of stack holders, a stack forming receptacle, a rotary carrier for said receptacle, and intermittently operating means for moving the lowermost article in said 15 holders in succession edgewise from said holder to a delivery point above said receptacle whereby said article is delivered flatwise into said receptacle.
4. An assorting machine comprising a circular series of stack holders each having a laterally extending guide, a series of feed devices slidable in said guides, means for operating said feed devices, a traveling stack forming receptacle to which said feed 25 devices deliver, and means for moving said receptacle.
5. An assorting machine comprising a circular series of radially extending guides, a series of feed devices slidable in said guides 30 and having provision for receiving a single article, a series of stack holders mounted each above one of said guides, means for operating said guides in succession, a traveling stack receptacle receiving from said 35 feed devices in succession, and means for moving said receptacle.
6. An assorting machine comprising a circular series of stack holders, a traveling stack forming receptacle having means for 40 forming a stack of variable height, means delivering from said holders to said receptacle, and operating means for said receptacle and for said delivery means.
7. An assorting machine comprising a series of vertical stack holders, article feeding means therefor, a traveling stack forming receptacle having a retractive article supporting device, means for operating said receptacle, and means related to said supporting device for limiting its retractive 50 movement.
8. An assorting machine comprising a series of vertical stack holders, article feeding means therefor, a traveling vertical stack forming receptacle having a retractive article sustaining device, means for intermittently operating said article feeding means and said receptacle relatively, and means related to said sustaining device for permitting the gradual retractive movement of said sustaining device during traveling 55 movement of said receptacle.
9. An assorting machine comprising a traveling stack forming receptacle having a retractive article sustaining device, means 60 for delivering articles to such receptacle, means acting to limit the retractive movement of said sustaining device during a part of the travel of said receptacle, means for advancing said sustaining means to its initial point of location, and means for operating said receptacle.
- 10 10. An assorting machine comprising a stack forming receptacle having retractive article sustaining means, a series of article delivery means delivering in succession to such receptacle, and means related to such sustaining means for limiting the retractive movement of said sustaining means relative to the operation of said delivery means.
- 11 11. An assorting machine comprising a traveling stack forming receptacle having retractive article sustaining means, a series of article carrying means delivering to said receptacle, means for operating said receptacle, and means for limiting the retractive movement of said sustaining means, said limiting means permitting the gradual retraction of said sustaining means without shock.
- 12 12. An assorting machine comprising a circular series of vertical stack holders, article feed devices therefor delivering at points located laterally from said holders, a vertical stack forming receptacle adapted to receive in succession at such points of delivery a rotatable carrier on which said receptacle is mounted, a plunger slidable in said receptacle, and an inclined way for limiting the movement of said plunger.
- 13 13. An assorting machine comprising a circular series of stack supports, a rotatable carrier, a circular series of stack forming receptacles mounted on said carrier, means for feeding articles from said supports to said receptacles, means for operating all of said feeding means in unison, and means for intermittently operating said carrier.
- 14 14. An assorting machine comprising a circular series of vertical stack holders, a series of feed devices therefor, a rotatable carrier located below said stack holders, a series of stack forming receptacles mounted on said carrier, a plunger slidable in each of said receptacles, a circular inclined way on which members of said plungers travel, and organized mechanism for intermittently rotating said carrier and for operating said feed devices.
- 15 15. An assorting machine comprising a series of stack supports, a carrier movable with respect to said supports, a stack forming receptacle pivotally mounted on said carrier, means for feeding articles in succession from said supports to said receptacle, and organized operating means.
- 16 16. An assorting machine comprising a circular series of stack supports, a carrier rotatably mounted, a stack forming receptacle pivotally mounted on said carrier,

means for feeding articles in succession from said supports to said receptacle, a receiver, means for effecting the swinging of said receptacle toward said receiver, and organized 5 operating means.

17. An assorting machine comprising a series of stack supports, a traveling stack forming receptacle pivotally mounted and having a slidable plunger, means for feeding articles from said supports to said receptacle, means for limiting the retractive movement of said plunger, means for swinging said receptacle, and means for projecting said plunger to eject the contents of said 10 receptacle.

18. An assorting machine comprising a circular series of stack holders, a series of feed devices therefor, a rotatable carrier, a series of stack forming receptacles pivotally 20 mounted on said carrier and adapted to receive articles from said feed devices, plungers slidable in said receptacles, means for limiting progressively the retractive movement of said plungers, and a single means 25 operating to engage and swing said receptacles at one point in the rotation of said carrier.

19. An assorting machine comprising a circular series of stack supports, a stack receiver fixed with relation to the circle of 30 said supports, a pivotally mounted traveling stack forming receptacle, means for feeding articles from said supports to said receptacle, means for intermittently operating said receptacle, means located adjacent said stack receiver for swinging said receptacles, and means for ejecting the formed stack from 35 said receptacle on to said stack receiver.

20. An assorting machine comprising a circular series of stack supports, a rotary 40 carrier, a series of stack forming receptacles pivotally mounted on said carrier, plungers slidable in said receptacle, an inclined circular way on which said plungers travel and 45 having an opening between its high and low points, means for swinging said receptacles, means for projecting said plungers, and means for guiding said plungers on to the high point of said circular way.

21. An assorting machine comprising a traveling stack forming receptacle pivotally mounted, a plunger slidable in said receptacle, means for limiting the retractive movement of said plunger, means for effecting 50 the swinging of said receptacle, means for projecting said plunger while the receptacle is in a horizontal position, and a guide for engaging said plunger and preventing its retraction during the recovery 55 movement of said receptacle.

22. An assorting machine comprising a rotary carrier, means for operating said carrier intermittently, a series of stack forming receptacles pivotally mounted on said 60 carrier, plungers slidable in said carriers,

an inclined circular way on which said plungers travel, a projecting device for said plungers located adjacent the low point of said way, a guide for engaging said plungers when projected to guide them to the 70 high point of said way, a receiver and means for swinging said receptacles toward said receiver.

23. In an assorting machine of the nature described a traveling stack forming receptacle pivotally mounted and having an engageable member, a lever pivotally mounted and out of engagement with said member, means for swinging said lever at times into engagement with said member to effect the 75 swinging of said receptacle and mechanism adapted to be brought into operation after said receptacle is swung to eject the contents thereof.

24. In an assorting machine of the nature 80 described a traveling stack forming receptacle mounted to swing and having a slide- 85 able stack sustaining member, means for swinging said receptacle to the horizontal position, and means operating to project 90 said plunger when said receptacle is so swung.

25. An assorting machine comprising a rotary carrier having a series of radially extending brackets, frames pivotally mounted 95 on said brackets and having engageable members, receptacles mounted on said frames, a pivoted arm adapted when swung to engage said frame member to effect the swinging of said frame, mechanism for effecting the intermittent rotation of said carrier, a receiver adapted to receive from said receptacle when swung and means operated by said mechanism for intermittently swinging 100 said pivoted arm.

26. An assorting machine comprising a rotary carrier having a series of radially extending brackets, frames pivotally mounted 110 on said brackets and having engageable members, receptacles mounted on said frames, plungers slidable in said receptacles, a pivot arm adapted to engage said frame member to effect the swinging of said frame, a plunger projecting mechanism, driving 115 means for effecting the intermittent rotation of said carrier, means operated by said driving for intermittently swinging said arm, and means operated by said driving means for intermittently actuating said plunger projecting mechanism.

27. An assorting machine comprising a pivotally mounted traveling stack forming receptacle having a slideable ejector, means for swinging said receptacle, a receiver positioned to receive a stack of articles from 125 said receptacle, and means for operating said ejector when the receptacle is swung to eject a stack of articles from said receptacle on to said receiver.

28. An assorting machine comprising a 130

pivottally mounted stack receptacle having a slidable ejector, a receiver positioned relative to the swinging of said receptacle, and comprising a pair of spring resisted movable stack receiving members, means for swinging said receptacle, means for operating said ejector, and means operating to force a stack of articles sustained by said members between said members in opposition to the resistance of the springs thereof. 10
